UNITED STATES PATENT OFFICE.

JACK NAUD AND SPERO MOCHE, OF ELGIN, ILLINOIS.

DOG RACE TRACK.

Application filed June 1, 1927. Serial No. 195,779.

This invention relates to dog racing devices, and particularly to certain improvements upon the dog racing device shown in our pending application for patent, Serial 5 No. 171,304, filed on the 26th day of February, 1927.

One of the objects of the present invention is to provide means whereby the rabbit at any desired part of the course may be 10 caused to leap into the air as if jumping a hurdle.

A further object is to provide a spring suspension for the motor of the rabbit carriage.

15 A still further object is to provide wheels disposed to bear against each side of the track so as to prevent any lateral movement of the carriage.

Other objects will appear in the course 20 of the following description.

Our invention is illustrated in the accompanying drawings, wherein:—

Figure 1 is a transverse section of a dog race track showing one of the supporting 25 posts in elevation;

Figure 2 is a side elevation of a portion of the track and carriage operating thereon;

Figure 3 is a vertical sectional view showing the carriage in elevation or looking 30 toward one end thereof.

Referring to these drawings, 10 designates a wooden track which, of course, has any desired extent and may be a straightaway track or a curved track, as desired.

35 This track is supported by means of the I-beam 11 which is bolted to the bracket 12 which projects outward from any suitable pole or support or any other overhead structure. We do not wish to be limited

40 to the particular construction of the track. We have shown the I-beam as being formed of two channel irons to permit the passage of electric wires but, of course, are not limited to this. The track 10 carries upon 45 its upper face the wear plates 13.

The carriage upon which the rabbit is supported includes the motor supporting frame 14. The forward end of this frame has a forwardly projecting lug 15 and a

50 two-armed yoke 16 is pivotally engaged with this lug 15, the two arms 16 extending upward and inward around the track 10 and carrying upon their extremities the wheels 17 which bear upon the wear plates 13.

55 The rear end of the motor supporting frame 14 is also formed with a rearwardly pro-

jecting lug or lugs 18 having the yoke arms 19 operatively engaged therewith, which extends upward and then inward over the track and carry the wheels 20 which also 60 rest upon the wear plates 13. The lower end of the yoke 19 is formed with a downwardly depending pin 21 which extends through an aperture in the lug 18 and the lug 18 rests upon a coiled compression 65 spring 22 which surrounds the rod 21 and at its lower end bears against a nut 23 carried by this rod. Thus one end of the motor frame is spring-supported, thus accommodating irregularities in the track. 70

Mounted upon the motor shaft 24 are the relatively large dished wheels 25 carrying preferably the rubber tires 26 which bear against the under face of the track 10, these 75 wheels constituting means whereby the carriage may be driven. The spring 22, it will be seen, urges these wheels upward against the under face of the track so as to secure a good tractive engagement therewith. Also mounted upon the frame of the motor or 80 upon the yokes 16 are arms 27 which carry upon them the rubber-tired wheels 28 which bear against the opposite faces of the vertical web of the I-beam 11. These arms 27 may be mounted in any suitable manner as, 85 for instance, in the manner illustrated in our prior application, but it will be noted that in the prior application these arms carried rollers of relatively small diameter, whereas the wheels 28 are of relatively large 90 diameter. These wheels 28 prevent the motor and its supporting frame or yoke from any tendency to twist upon the track and cause the carriage to take all the curves of the track. 95

The rabbit 29 is mounted on the end of a depending arm 30. The upper end of this arm is carried upon a transverse rock shaft 31 mounted in suitable bearings in the yoke arms 16, the arm supporting the rabbit extending downward and forward, though it will be understood that the rabbit-supporting arm might trail behind the carriage, assuming that the carriage is moving in a reverse direction to that illustrated in Figure 2. The shaft 31 carries an upwardly and rearwardly projecting arm 32 having a roller 33 or wheel at its upper end. At intervals along the track or at any desired place along the track, there is disposed the downwardly extending protuberance 34. Normally the roller 33 bears against the under 100 105 110

face of the track 10, but when the roller reaches this protuberance, the rear end of the arm 32 will be depressed and the rabbit will have lifted so that the rabbit can under 5 these circumstances pass over a hurdle or other obstruction on the track, thus causing the dogs to jump the hurdle when they reach it. There may be as many of these protuberances 34 as desired.

10 For the purpose of lighting the track, we have provided the upwardly extending tubular post 35 embedded at its lower end in concrete and having the brace 36 which extends upward to the lateral arm 37 of the post. This post is hollow, as is the arm. The I-beam 11 is attached to the extremity of the arm by bolts or other suitable means and the wires 38 which lead from any suitable source of energy pass through these 20 hollow posts 35 and are then carried to the metallic plates 14 which engage the metallic trolley wheels 17. From thence the current passes by wire to the motor in the manner illustrated in our prior application. We do 25 not wish to be limited to any particular means for conducting the electric current to the motor, as this may be accomplished in any obvious manner. The current might be taken, for instance, from the wheels 28 or 30 from the wheels 17 or the wheels 20, as desired. Electric lights 39 may also be mounted upon the braces 36 and connected to a source of current so as to illuminate the track.

35 While we do not wish to be limited to this, preferably the post 35 will be formed in two sections, a short section which is inserted in a concrete base and a longer upper section, these sections to be connected by a 40 screw-threaded coupling 40 so that if it be desired to shift the track from one place to another, the upper sections of the post 35 may be removed from the lower sections without the necessity of tearing up the concrete bases or constructing new posts.

45 We claim:—

1. A dog racing apparatus including an overhead track, a carriage operating on the track, a motor mounted on the carriage, 50 means for conducting electricity to the motor, a lure support pivotally mounted upon the carriage and normally extending downward therefrom, the lure support having an arm, and a roller engaging the under face of the track, the under face of the track being provided at intervals with protuberant portions acting to depress the roller and elevate the lure-supporting arm.

2. A dog racing apparatus including an 60 overhead track, a carriage disposed below the track, a motor mounted upon the carriage and disposed below the track, hangers engaged with one end of the carriage and extending upward, trolley wheels carried by 65 said hangers and bearing against the track,

trolley wheels disposed in advance of the carriage and having members extending downward therefrom, a stem extending downward from said hangers and extending through the carriage, and a spring engaged 70 at one end with said stem and at the other end with the carriage whereby to cause the weight of the carriage to yieldingly urge the forward trolley wheels downward against the track, and a lure depending from the 75 carriage.

3. A dog racing apparatus, including an overhead track comprising a longitudinally extending vertically disposed I-beam formed of two channel sections spaced from each other, a horizontally disposed beam and constituting a track supported upon said I-beam below the same and extending laterally beyond the I-beam, metallic conductors carried upon said second named beam, 80 electrical connections extending downward between the channel members forming the I-beam and engaged with said metallic conductors, a carriage disposed below the I-beam and having hangers extending upward exteriorly of the second named beam and then inward, the hangers carrying metallic rollers engaging said metallic conductors, a motor mounted upon the carriage and in electrical engagement with the rollers, and 85 a lure depending from said carriage.

4. A dog racing apparatus comprising a longitudinally extending overhead supporting structure comprising a longitudinally extending member and a horizontally disposed member below the first named member and projecting laterally beyond the same, a carriage disposed below the second named member, a motor supported by the carriage, wheels driven by the motor and bearing against the under face of the second named member, hangers extending upward from the carriage and inward over the upper face of the second named member, conductors mounted upon the second named member, trolley rollers mounted upon said hangers and bearing against said conductors, means carried by said hangers for preventing lateral movement of the carriage with relation to the second named member and a depending lure supported by said carriage.

5. A dog racing apparatus comprising an overhead track, a carriage disposed below the track, a motor supported by the carriage, wheels driven by the motor and operatively 120 engaging the under face of the track, trolley wheels engaging the upper face of the track and having hangers engaging the carriage, certain of the trolley wheels being resiliently engaged with the carriage to yieldingly urge 125 the motor upward against the track and thus urge the driving wheels against the under face of the track, and a lure dependingly supported by the carriage.

6. A dog racing apparatus comprising an 130

overhead track, a carriage disposed below the track, a motor mounted thereon, hangers pivotally engaged with one end of the carriage and extending upward above the track, supporting and electrically conductive rollers mounted upon said hangers and bearing against the upper face of the track, conductors on the track with which the rollers engage, rollers disposed above the front end of the carriage and bearing against the track, a spring connection between the last named rollers and the adjacent end of the carriage and acting to urge the carriage upward and the last named rollers downward, driving wheels mounted upon the carriage 15 and driven by the motor and engaging the under face of the track, and a lure dependingly supported by the carriage.
